(57) **CLAIM**

The ornamental design for a firearm as shown and described.

DESCRIPTION

FIG. 1 is a right, rear perspective view of a firearm in accordance with our design;

FIG. 2 is a left, rear perspective view of the firearm of FIG. 1;

FIG. 3 is a left side elevational view of the firearm of FIG. 1;

FIG. 4 is a right side elevational view of the firearm of FIG. 1;

FIG. 5 is a top plan view of the firearm of FIG. 1;

FIG. 6 is a bottom plan view of the firearm of FIG. 1;

FIG. 7 is a rear elevational view of the firearm of FIG. 1;

FIG. 8 is a front elevational view of the firearm of FIG. 1; and,

FIG. 9 is a close-up partial perspective view of the portion of the firearm indicated in FIG. 2.

The evenly broken lines depict unclaimed portions of the firearm; the dash-dot type broken lines disclose unclaimed boundaries of isolated and enlarged views; the broken lines form no part of the claimed design.

1 Claim, 6 Drawing Sheets
